UNITED STATES PATENT OFFICE.

EDWARD ERNEST BERNHARD, OF ST. MARY CRAY, ENGLAND.

MACHINE FOR MARKING SHOW-CARDS OR TICKETS.

1,134,812.

Specification of Letters Patent.

Patented Apr. 6, 1915.

Application filed August 1, 1914. Serial No. 854,521.

To all whom it may concern:

Be it known that I, EDWARD ERNEST BERNHARD, a subject of the King of Great Britain, residing at Northfields, St. Mary Cray, 5 Kent, England, have invented a new and useful Improvement in Machines for Marking Show-Cards or Tickets, of which the following is a specification.

This invention relates to means by which 10 cardboard window tickets or show cards can be produced by the use of type furnished with cutting edges.

The method of operation is to lay a sheet 15 of colored paper on the cardboard constituting the ticket; the type is then brought into contact with the paper, and pressure applied by means of the press herein described. This causes the cutting edge of the type to cut out the characters or letters required, and to 20 embed them firmly into the sheet of cardboard, in such a manner that they will remain in position without the use of glue, gum or other adhesive.

According to this invention I provide a 25 hold for the type which slides in grooves cut in stops at either end of the moving plate of the press, and I support smaller type than those of the largest size which the holder is adapted to carry by means of 30 spring clips which clip over the sides of the holder.

The invention is illustrated in the accompanying drawing in which—

Figure 1 is a sectional elevation of the press. Fig. 2 is a section on the line A A 35 Fig. 1 and shows one of the largest type in position in the holder. Fig. 3 is a view similar to Fig. 2 but showing a small type supported by clips while Figs. 4 and 5 are a side view and a plan of a clip. 40

The moving plate *a* of the press has at each end a stop *b* in which is cut a groove to receive a holder consisting of a rectangular frame *c* on the back and front of which rest shoulders *d* of the type *e* of largest size. For holding type of smaller size 45 I employ spring clips *f* which embrace the back and front of the holder as shown in Fig. 3 while their inner ends lie beneath the shoulder *d'* of the smaller type *e'*. 50

What I claim is:—

In a press adapted for making show cards and the like the combination of grooved stops at either end of the moving plate, a 55 rectangular type holder adapted to slide in the grooves and spring clips adapted to embrace part of the holder and to support type of a size smaller than the largest which the holder can carry.

EDWARD ERNEST BERNHARD.
